Large Size Toilet Paper Holder with Shelf. Kuhome (online) 7 pgs. Available May 21, 2022. [Retrieved Mar. 15, 2023] <https://www.amazon.com/Kuhome-Double-Duty-Flushable-Dispenser-Organizer/dp/B0B1WGSQM1> (Year: 2022).*

Primary Examiner — Marie D. Fast Horse*Assistant Examiner* — Jennifer Sierra Yosinski(74) *Attorney, Agent, or Firm* — Jose Cherson Weissbrot(57) **CLAIM**

The ornamental design for a toilet paper holder with shelf, as shown and described.

DESCRIPTION

FIG. 1 is a front perspective view of a toilet paper holder with shelf, showing my new design;

FIG. 2 is rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 2;

FIG. 11 is a partial enlarged view of FIG. 2;

FIG. 12 is a partial enlarged view of FIG. 2; and,

FIG. 13 is a partial enlarged view of FIG. 2.

The dash-dot broken lines depict reference to the enlargements shown in the figures and form no part of the claim.
